CLIPPER FOR OBTAINING HAIR DENSITY SAMPLES

John I. Hardy, Laurel, Md.

Application August 6, 1942, Serial No. 453,778

11 Claims. (Cl. 30—197)

(Granted under the act of March 3, 1883, as amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to a means for removing a sample of hair, such as wool, for example, from a hair covered surface of predetermined area for the purpose of determining the fiber density characteristics of the sample.

The accuracy of results in wool density sampling depends primarily on the accuracy of dimensions in laying off the predetermined area. In the prior art, this is accomplished by use of calipers so arranged as to cleave the wool along two parallel lines a predetermined distance (1 centimeter, say) apart. An ordinary clipper is then inserted in the cleavage lines, and the hair is clipped from the adjacent surfaces. The wool is next cleaved along two parallel lines perpendicular to the first two lines and the adjacent wool clipped. The sample of wool in the area so determined is tied and clipped from the skin.

This manner of removing the sample has disadvantages; it is tedious, and, unless extreme caution be taken, the area is none too accurately laid-off; it is difficult, if not impossible, to follow such procedure with dense or felted fleeces; and removing the hair from the adjacent surfaces disturbs them and makes it difficult to obtain a plurality of samples from neighboring areas.

The objects of this invention are to provide an improved method of obtaining hair density samples; to provide means whereby samples may be easily and quickly obtained from a predetermined accurately laid-off area; to provide means whereby a plurality of samples may be obtained from neighboring areas; to provide a clipper for obtaining density samples which will accurately lay off a surface of predetermined width and simultaneously remove the hair from surfaces adjacent thereto; and to provide improvements in clippers generally.

The means for obtaining hair density samples and the improvements in clippers are illustrated in the accompanying drawing in which:

Figure 1 is a side elevation of a clipper on a reduced scale,

Figure 2 is a section on the line 2—2 of Figure 1 in full size scale, and

Figure 3 is a section on the line 3—3 of Figure 2.

The clipper is driven by a conventional electric

motor 1 to which the gear case 2 and handle 3 are attached. The clipper comb 4 is fixedly attached to a plate 5 by suitable securing means, such as screws 6 and dowel pins 7, and the plate 5 is fixedly attached to the gear case by suitable securing means, such as screws 8 and dowel pins 9. The cutter 10 is fixedly attached to the driver block 11 by suitable securing means, such as dowel pins 12, and the driver block is pivotally mounted on a pivot pin 13.

The driver block is oscillated on its pivot by rotating shaft 14, which is driven by the motor and which is provided with a cam 15 operating in a slot 16 in the driver block, thus reciprocating the cutter relative to the comb.

The comb comprises two arms 17 and 18 which are rigidly secured together, being made integral in the particular embodiment shown. These arms are provided with comb teeth 19, the points of adjacent teeth being accurately spaced apart a predetermined distance (1 centimeter, say). The two arms are considerably longer than the comb of an ordinary clipper, allowing an unobstructed clearance space 20 of considerable length between them. This arrangement of the adjacent teeth and clearance space provides a means for laying off a predetermined width strip of hair-covered surface, thus performing the function of the caliper previously used for this purpose.

The cutter also comprises two arms 21 and 22 rigidly secured together and mated with the comb arms, in such manner that the cutter arms and teeth always clear space 20. Each comb arm and its mating cutter arm, such as 17 and 21, for example, provides a means for removing a swath of the hair from a hair-covered surface while the other comb arm and its mating cutter arm provides a means for simultaneously removing another swath, the two swaths being parallel and spaced apart a predetermined distance, corresponding to the spacing of the points of adjacent teeth of the comb arms.

Due to the length of the comb and cutter arms special provisions have been made to provide adjustable tension means remote from the clearance space for holding the cutter tightly against the comb. Such means comprises a pin, such as a thumb screw 23, loosely fitting an aperture 24 in a portion 25 of the driver block, which portion extends laterally or normal to the plane of its motion. The thumb screw is seated to pivot on the gear case at point 26. This point is on a line normal to the plane of motion of the cutter and containing the axis of pivot pin 13. A spring

seat 21 is threaded on the thumb screw and has flattened sides for non-rotatable and linear movement in a pocket 28 in portion 25 of the driver block. A compression spring 29 exerts force between the spring seat and driver block. The tension of the cutter on the comb is adjusted simply by turning the thumb screw.

The clipper is used in the following described manner: Assuming that it is desirable to obtain a sample of wool, the sheep is laid down and made to relax so that the skin at the sampling area is unstretched. A pair of swaths are cut in a straight line, leaving a row of an accurately laid-off predetermined width between them. Due to the length of the arms and clearance space 20, these swaths may be cut several inches long without unduly crowding the wool in the clearance space and disturbing the underlying skin. Swaths are next cut perpendicular to the first swaths across the row, leaving standing the sample of wool on an accurately laid-off predetermined skin area. Several such cross swaths may be cut, leaving several neighboring samples.

In order to maintain the fibers of the samples in alignment for subsequent measurements, they are bound together with thread and then cut off, or they may be clamped with a haemostat, instead of tied and the ends sealed with wax or plastic solution after they have been cut off.

Many advantages over the prior procedure arise from the use of the sampling means herein disclosed. The samples are taken with much greater speed; elaborate technique is not required; the sample areas are laid-off with greater precision; samples may be taken from nearer neighboring areas; and dense and felted fleeces may be sampled which could not be sampled by the prior procedure. A mean density value is obtained by the means of this invention with a precision of 3%, which is of greater accuracy than heretofore obtained. This results in more precise knowledge of samples and the possibility of more thorough sampling.

Having thus described my invention, what I claim is:

1. A clipper comprising a comb, a cutter mating with the comb, means for reciprocating the cutter relative to the comb, and means for tensioning the cutter on the comb comprising a portion fixed to the cutter remote from its front end and extending laterally therefrom, and spring means exerting force against the free end of the laterally extending portion in a direction substantially parallel to the plane of movement of the cutter.

2. In a clipper for obtaining hair density samples, means for laying off a predetermined width strip of hair covered surface and means for simultaneously removing the hair from areas adjacent the strip.

3. A clipper for obtaining hair density samples comprising means for clipping a swath, and means connected to the first-mentioned means for simultaneously clipping another swath parallel to and spaced a predetermined distance from the first-mentioned swath.

4. In a clipper, a plurality of spaced apart comb arms fixedly secured together at their rear ends.

5. In a clipper, a plurality of spaced apart comb arms fixedly secured together in such manner that a clearance space opening at the forward ends of the arms is left between them.

6. A clipper for obtaining hair density samples comprising a comb formed by two parallel arms

defining an elongated clearance space between them, said arms being integrally secured together at their rear ends and provided with comb teeth at their free ends, the points of the two adjacent teeth on the two arms being spaced apart a predetermined distance, a cutter formed by two parallel arms mating with the arms of the comb, means for reciprocating the cutter relative to the comb comprising a driver block mounted on a pivot pin for oscillating movement relative to the comb and fixedly secured to the cutter, said block having a portion extending normal to the plane of its movement, and adjustable means for tensioning the cutter on the comb comprising a thumb screw loosely fitting through an aperture in the extending portion of the driver block, the end of the screw being seated on a pivot point on a line normal to the plane of movement of the cutter and containing the axis of the pivot pin, a spring seat threaded on the screw between the pivot point and the extending portion, said spring seat being fixed against rotation and movable linearly relative to the extending portion, and a compression spring exerting force between the spring seat and the extending portion.

7. A clipper for obtaining hair density samples comprising a comb formed by two elongated parallel arms defining an elongated clearance space between them, said arms being fixedly secured together at their rear ends and provided with comb teeth at their free ends, a cutter formed by two parallel arms mating with the arms of the comb, means for reciprocating the cutter relative to the comb, and means for exerting force on the cutter to hold it against the comb, said means being positioned at a point rearwardly of the cutter arms whereby the cutter arms and clearance space are free from obstructions.

8. In a clipper for obtaining hair density samples, a comb formed by two parallel arms defining a clearance space between them, said arms being fixedly secured together at their rear ends and provided with comb teeth at their free ends, the points of the two adjacent teeth on the two arms being spaced apart a predetermined distance.

9. A clipper comprising a comb, a cutter mating with the comb, means for reciprocating the cutter relative to the comb comprising a driver block mounted on a pivot pin for oscillating movement relative to the comb and fixedly secured to the cutter, said block having a portion extending normal to the plane of its movement, and adjustable means for tensioning the cutter on the comb comprising a thumb screw loosely fitting through an aperture in the extending portion of the driver block, the end of the screw being seated on a pivot point on a line normal to the plane of movement of the cutter and containing the axis of the pivot pin, a spring seat threaded on the screw between the pivot point and the extending portion, said spring seat being fixed against rotation and movable linearly relative to the extending portion, and a compression spring exerting force between the spring seat and the extending portion.

10. A clipper comprising a comb, a cutter mating with the comb, means for reciprocating the cutter relative to the comb comprising a pivotal mounting of the cutter relative to the comb on an axis normal to the plane of movement of the cutter, said cutter being provided with a portion extending laterally from the plane of movement of the cutter, and means for tensioning the cutter on the comb comprising a pin ex-

tending loosely through an aperture in the laterally extending portion, the end of the pin being seated on a pivot point on a line normal to the plane of movement of the cutter and containing the axis of the pivotal mounting, a spring seat on the pin between the pivot point and the extending portion, and a compression spring exerting force between the spring seat and the extending portion.

11. A clipper comprising a comb, a cutter mat- 10

ing with the comb, means for reciprocating the cutter relative to the comb, and means for tensioning the cutter on the comb comprising a portion 5 fixed to the cutter remote from its front end and extending laterally therefrom, and spring means exerting force against the free end of the laterally extending portion for resiliently holding the cutter against the comb.

JOHN I. HARDY.
